CLAIM

The ornamental design for a mat sensor, as shown and described.

DESCRIPTION

FIG. 1 is a front perspective view of a mat sensor showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The uneven-length broken line defines the bounds of the claimed design and forms no part thereof. The even-length broken lines depicting the remainder of the mat sensor form no part of the claimed design.
